US00D851111S

(12) **United States Design Patent** (10) **Patent No.:** **US D851,111 S**
Dye et al. (45) **Date of Patent:** **** Jun. 11, 2019**

(54) **ELECTRONIC DEVICE WITH GRAPHICAL USER INTERFACE**

(71) Applicant: **Apple Inc.**, Cupertino, CA (US)

(72) Inventors: **Alan C. Dye**, San Francisco, CA (US); **Jonathan P. Ive**, San Francisco, CA (US); **Behkish Johnnie Manzari**, San Francisco, CA (US); **Grant R. Paul**, San Francisco, CA (US); **William A. Sorrentino, III**, San Francisco, CA (US); **Andre Souza Dos Santos**, Santa Clara, CA (US); **Christopher Wilson**, San Francisco, CA (US)

(73) Assignee: **Apple Inc.**, Cupertino, CA (US)

(**) Term: **15 Years**

(21) Appl. No.: **29/616,884**

(22) Filed: **Sep. 9, 2017**

(51) LOC (11) Cl. **14-04**

(52) U.S. Cl.

USPC **D14/486**

(58) **Field of Classification Search**

USPC **D14/485-495**

(57)

CLAIM

The ornamental design for an electronic device with graphical user interface, as shown and described.

DESCRIPTION

FIG. 1 is a front view of an electronic device with graphical user interface showing the claimed design; and, FIG. 2 is a front view of the claimed design shown in environment.

The broken lines in the figures show an electronic device having a display screen, or show environment, and form no part of the claimed design.
